UNITED STATES PATENT OFFICE.

LEON MARTIN, OF GENEVA, SWITZERLAND.

PAPER-FEEDING MECHANISM.

1,373,254.

Specification of Letters Patent. Patented Mar. 29, 1921.

Application filed March 17, 1920. Serial No. 366,498.

To all whom it may concern:

Be it known that I, LEON MARTIN, citizen of Switzerland, residing at Geneva, in the Confederation of Switzerland, have invented certain new and useful Improvements in Paper-Feeding Mechanism, of which the following is a specification.

The object of the present invention is an automatic paper layer machine for printing 10 presses or other machines which are to be fed with sheets of paper. This machine comprises at least one pair of movable arms provided with suction devices intended to take the sheets up from a pile and to deliver the 15 same to clamps carried by said arms which clamps will seize the edges of said sheets and advance the latter to the respective machines.

The paper feeding mechanism may be fitted 20 also with blowing nozzles coöperating with the suction devices for delivering the sheets of paper to the clamps. These nozzles may be connected by means of flexible pipes to a suction device located near the paper 25 feeding mechanism and the suction periods may be controlled by a system of cams operated by the driving shaft of the machine.

The machine may also comprise a movable table carrying a bracket provided with a 30 slide, which bracket may be fixed by means of a screw and whereon may be placed a movable straight edge adapted to move laterally in the direction in which the sheets have to be advanced.

The brackets of the driving shaft are 35 adjustable to position so as to adapt the paper feeding mechanism to all widths of sheets to be fed.

In the annexed drawings two working 40 forms of the paper feeding mechanism are shown as examples.

Figure 1 is a diagrammatical side view of the first working form.

Figs. 2 and 3 are plan views, the first of the 45 delivery device taken in the direction of the arrow A of Fig. 1, the second a plan of the driving device and of the suction device taken in the direction of the arrow B in Fig. 1.

50 Figs. 4 and 5 are a side view and a plan of one of the clamps intended to seize the sheets.

Figs. 6 and 7 are a plan and an end view

respectively of one of the separating suction members.

55

Fig. 8 is a side view of a detail.

Fig. 9 is a side view, and

Fig. 10 a plan of a second working form of the machine.

Fig. 11 a front view of the machine table 60 and of the movable plate located on said table.

Figs. 12, 13 and 14 are on a larger scale than 65 8, 9 and 10, a front view, a plan, and a side view of the controlling device of the suction members and of the nozzles.

Fig. 15 is likewise on a larger scale than 70 Figs. 8 and 10, a side view of another working form of the device producing the oscillation of the suction members.

75

The paper feeding mechanism according to Figs. 1 to 8 is arranged on a horizontal table *a* supporting a pile *a*¹ of paper sheets and resting with one end on the edge of an inclined table *b*. The table *a* carries on brackets *c* and *c*¹ a driving shaft *d* with a driving pulley *d*¹. The movable arms constructed with cross-bars *e*, *e*¹ and *e*², *e*³, joined in pairs at the fore ends by bars *f*, *f*¹ respectively, are mounted loosely on shaft *d*. Two 80 bevel gear wheels *d*², *d*³ are keyed to shaft *d* between the bars *e*, *e*¹ and *e*², *e*³ and mesh with bevel wheels *g*, *g*¹. The latter are driven in opposite directions and are keyed to the ends of shafts *h*, *h*¹, arranged between 85 the bars *e*, *e*¹ and *e*², *e*³ respectively, and to the other ends of which are keyed the bevel wheels *g*², *g*³. These latter wheels are meshed with bevel wheels *i*, *i*¹ keyed to inclined shafts *k*, *k*¹, respectively and these 90 shafts are mounted with the pieces *f*, *f*¹ respectively, which in the lower ends on the table *a* serve as intermediate bearings for the movable arms. Said shafts *k*, *k*¹ also support cross bars *l*, *l*¹ attached to the pieces *f*, 95 *f*¹ by means of screws *f*², *f*³ and provided at their fore ends with axis *m*, *m*¹, secured by said cross bars. The lower ends of the axis *m*, *m*¹ serve as supports for the ends of the movable arms.

100

The delivery device comprises two chains *n*, *n*¹, operated in the direction indicated by the arrows 1 and 2. When the machine is moving, by means of sprocket wheels *o*, *o*¹ and *o*², *o*³, shafts *k*, *k*¹ and gears *i*, *i*¹, *g*², *g*³ 105 and each carrying a clamp *p*, *p*¹. The open-

ing of said clamps for seizing or for releasing the paper sheets is controlled by the members r , r^1 and r^2 , r^3 provided at the ends of the cross bars l , l^1 . These clamps (Figs. 5 4 and 5) are formed with two blades p^2 , p^3 screwed unto the links of the chains n , n^1 . The upper blades p^2 carry an elbow arm p^4 adapted to oscillate on an axis p^5 fixed to the plate p^2 . The end p^6 of the elbow arm 10 p^4 is kept in position against blade p^3 by means of a resilient device consisting of a rod p^8 held in position by a tension spring p^9 . The extremity p^{10} of the elbow arm p^4 is rounded off and is operated by one of the 15 members r , r^1 and r^2 , r^3 , respectively whenever it passes underneath of one of said members as will be explained farther on.

The separating suction members, two in number, are mounted at the ends of the cross 20 bars e , e^3 respectively, each of which presents to this end a rounded off extension whereon the separating members oscillate. These separating members, whereof one is represented at Figs. 6, 7 each constitute a 25 two armed bracket S , S^1 , S^2 arranged above and below the shafts h , h^1 respectively and adapted to oscillate on the extension of the cross-bars e , e^3 . The arms S^1 bear on cams S^3 fast at the ends of the shafts h , h^1 , said 30 cams producing the oscillating of the brackets S , S^1 , S^2 . On each arm S^2 and by means of a plate S^4 fast at the end of said arm S^2 , is mounted the cylinder S^5 of a pump, the piston of which is connected by 35 means of a connecting rod S^6 to a crank pin S^7 fast on a gear wheel S^8 meshing with a wheel S^9 fast on the end of the shafts h . The pump cylinder S^5 is provided at its bottom with a vent hole S^{10} which moves with 40 the cylinder S^5 and the arm S^2 and is intended to lift up the sheet of paper at the top of the pile a^1 on table a .

The machine is also provided with a device for a lateral regulation, shown in Figs. 45 2 and 8 and consisting in a straight edge t^1 fast on table b , (Fig. 2) and a straight edge t^2 movable on two parallel links t^3 , t^4 mounted on a bracket t^5 fast on table b and fitted 50 with a slide t^6 and a fastening screw t^7 which permits of bringing the movable straight edge t^2 into a desired position. This movable straight edge is provided with a projecting part t^8 against which a finger t^9 attached to chain h^1 will strike when the latter is moving, producing thereby the advancing of said straight edge t^2 , which, due to the parallel links t^3 , t^4 , will advance parallelly with the straight-edge t^1 , while moving in a longitudinal direction with the 55 paper. The movable straight-edge t^2 is brought back into its starting position after the finger t^9 has passed by the projecting part t^8 by means of a resilient contrivance not represented in the drawing.

60 The working of the machine is as follows:

The shaft d driving the bevel gear wheels d^2 , d^3 , will cause by means of the wheels g , g^1 , the shafts h , h^1 , the bevel gears g^2 , g^3 the moving of chains n , n^1 . The moving shafts h , h^1 will rotate also the separating suction 70 members by means of the cams S^3 and as a pile of paper sheets has been put on table a , the vent holes S^{10} of the separating members will, at a predetermined moment and under the action of the cams S^3 which may 75 be employed as a regulating contrivance to vary the action of the same on the separating members, will while oscillating stick close to the upper surface of the uppermost sheet of the pile and at the moment, when the cams S^3 carry the ends of the suction members upward, the vent holes S^{10} lift the sheet as the suction of the pumps S^5 takes place at the moment of the upward movement of said vent holes. The position of the clamps p , p^4 on the chains n , n^1 and the speed at which they move is such that the clamps seize the lifted sheet at the end of the lifting movement and when the suction of the vent holes ceases and carry the same over the inclined 85 table b so as to present it to a printing press for instance. Before seizing the lifted sheet the clamps p , p^4 pass underneath the members r or r^2 against which the parts p^{10} of their respective elbow lever p^4 will lean and will be opened thereby. This opening movement lasting but a short while will be stopped as soon as the said parts p^{10} are released from the members r or r^2 . The same parts p^{10} passing underneath the members r^1 , r^3 90 which are like the former and are mounted at the ends of the cross bars l , l^2 will cause the opening of the clamps p , p^1 in order to release the sheet of paper which will now glide upon the inclined table b where it will 95 be guided in the desired direction by the straight edges t^1 , t^2 . The gear working the separating members by suction and the delivery device are so designed as to cause the clamps to seize the sheets whenever they 100 have been lifted up by the separating members. These results may be easily obtained by adjusting the cams a^3 .

The brackets e , e^3 of the driving shafts d are adjustable to position to vary the distance between the shafts h , h^1 according to 115 the width of the paper sheets it being understood that the bevel wheels d^2 , d^3 , are mounted on feathers so as to slide on the shaft and the cross-bars e , e^1 and e^2 , e^3 , may also slide 120 on the shaft d .

The machine represented in Figs. 9 to 15 is arranged on a horizontal table i carrying a movable plate 2 with a pile 6 of sheets, said plate being adapted to oscillate and reciprocate on trunnions 4 provided at the inside. The machine rests with its fore end on an inclined table 5 . The horizontal table i carries brackets 6 and a bracket 6^1 located between the former in which is 125 130

mounted a shaft 7 fitted with a crank 7¹. Two movable arms 8, 9 are hinged to shaft 7 by means of hinges 10, 10¹, said arms being provided at their other ends with hinges 11, 11¹, hinging said arms to arms 8¹, 9¹. Bevel gear wheels 12, 12¹ and 13, 13¹, are adapted to transmit a rotating movement from shaft 7, to shafts 14, 14¹, lodged inside of said arms, while bevel gears 15, 15¹ transmit said movement to shafts 17, 17¹ by means of bevel gear wheels 16, 16¹, which shafts form the pins of the hinges 11, 11¹ and carry at their ends the sprocket wheels 18, 18¹, similar sprocket wheels 19, 19¹ being mounted at the fore ends of said arms 8¹, 9¹ and chains 20, 20¹ being mounted on said wheels. Each of these chains carry clamps 21 adapted to seize the sheets of paper.

20 The opening movement of said clamps for seizing the sheets of paper in the pile 3 and for releasing the lifted and conveyed sheets again is controlled by cams or rather by trip fingers which are not represented on the drawing, but which are provided on the shafts of the sprocket wheels. The fore ends 8¹, 9¹ of the movable arms are each provided with a bracket 22 presenting at its lower part a roller 23 adapted to contact 25 the inclined table 5. The brackets 6 carry also besides the shaft 7 two threaded rods 24, 25 one above the other, which extend between brackets 6 and 6¹. The rod 24 is attached to the hinge piece 10¹ by 30 means of a lug 26, and the rod 25 is attached to hinge piece 10 by means of a lug 27. Both rods 24, 25, are adapted to be turned by means of a crank 28 employed alternately on the one or the other rod in 35 40 order to regulate the distance between the movable arms. The height of the movable plate 2 oscillating on trunnions 4 may be adjusted by means of an elbow lever 29 pivoted on a trunnion 30 on one of the brackets 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900

The nozzles for lifting off the upmost sheet of the pile are mounted on brackets 34, 35, both alike, but only one 34 is represented in Figs. 12 to 14, and will be described here. The bracket 34 carries a metallic pipe 37 provided at its lower end with a sucking-nozzle 36 and connected at its upper end by means of a rubber hose 38 to a sucking device not shown. This bracket is fixed to an axis 44 (Fig. 12) mounted slidably within the hinge piece 11¹ fast on the movable arm 9. Bracket 34 is guided also by means of a rod 45 fast to said hinge piece 11¹ and its movements are controlled by means of an arm 46 connected by a link 47 to the bracket 34; said arm carrying a cam roller 48 guided by a cam 49 fast on shaft 14¹, which is operated by means of bevel wheels 13¹, 12¹, from the driving shaft 7. Said cam 49 will cause bracket 34 to be oscillated in a vertical direction and with it also the sucking nozzle. The metallic pipe 37 of the latter is fitted with a sleeve 50 fixed by means of two screw bolts 51 on said pipe and carrying a roller 52 guided by a guiding edge 53 fast to hinge piece 11.

Bracket 34 of the sucking device presents at its fore part a member 34¹ pivoted on said bracket so as to impart an oscillating movement to the sucking nozzle. A spring 54 connects the pins 55, 56, whereof 55 is fast on bracket 34 while the other pin 56 is fast on the hinge piece 11, and keeps the roller 48 in contact with the cam disk 49.

On the bracket 34 is also fixed a rod 57 supporting a blowing nozzle 39. This latter is provided with a nozzle 40 of a peculiar shape fitted to the end of a metallic tube 41 which is connected by a rubber hose 42 to an air compressor not represented. Both blowers and both sucking devices are similar.

The working of this paper feeding mechanism is as follows: From the driving shaft 7 the movement is transmitted by means of 110 bevel wheels 12, 12¹, 15, 15¹, 16, 16¹ to the chains 20, 20¹ and to the clamps 21, which will seize a sheet from pile 3, which sheet has been lifted by the effect of the blowing and sucking nozzles, the operating of which 115 is caused by the cams worked from the said shaft 7 in such a manner, that the blowing device will eject a jet of compressed air for separating the sheets, while the sucking device will be kept operating until the clamps 21 120 have seized the sheet lifted off by the sucking nozzles. At this moment the working of the blowing and sucking device is stopped and the sheet will be carried along by the clamps 21 on to the inclined table 5 where it 125 is left free by said clamps at the desired moment. The adjusting of the movable plate 2 in height is effected by hand by means

of the crank 33 and the distancing from each other of the movable arms 8, 9, is effected by the crank 28.

The sucking nozzles from the beginning 5 of the sucking action until this action is stopped, are raised together with the support 34 by means of the levers 46, 47 and the roller 48 by cam 49. Said nozzles will during this ascending movement be oscillated 10 by means of the roller 52 guided on the edges 53 of an irregular shape just so in order to impart to the sucking members this oscillating movement for better detaching the sheet on the top of the pile 3.

15 The oscillating device which is the same for both of the sucking members and whereof only one is described here consists of a guiding edge 60 pivoted on an axis 61 provided at its upper end and supported by a 20 bracket 62 arranged at the aft end of the hinge piece 11. This edge 60 is kept at an inclined position as represented in the drawing by a spring 63 fast at its upper end to the bracket 62 and leaning with its lower 25 end against a projection 64 attached to the edge 60. The roller 52 mounted on sleeve 50 fast to the pipe 37 of the sucking device travels, when the sucking member descends during the working of the machine, on the 30 back of the hinge piece 11 and is kept in contact with the same by means of a resilient contrivance not shown. It passes on the back side of the edge 60 and while descending pushes the latter in the direction of the 35 arrow (Fig. 15) but as soon as roller 52 has passed the edge 60 this latter is brought back by spring 63 into the inclined position and will have assumed the position shown in the drawing (Fig. 15). There the sucking 40 device is moved upward again under the effect of cam 49 and the roller 52 travels on the undulated part of the edge 60 against which it is kept in contact by the said resilient device, not shown, and when it reaches 45 the upper end of the edge it travels horizontally on the top of hinge piece 11 under the effect of said resilient device. This working form will cause the oscillating of the sucking members and cause a vertical 50 descending movement of the latter, so that the sucking nozzle 36 at the end of tube 37 will be laid flatly on the sheet, which is to be lifted and the horizontal movement imparted to the sucking device at the moment 55 when roller 52 travels on edge 60 will permit the introducing of the edge of the sheet lifted by the sucking nozzle into the clamps 31 carried by the chain 20.

This oscillating movement of the sucking 60 nozzles may be imparted to the same during their rising movement or during their descending movement according to the shape given to the edges 53.

The adjusting in height of the movable 65 plate 2 could be effected automatically by

the rotating shaft 7 operating by means of gear wheels the threaded rods 32 and the elbow lever 29.

The brackets 6, 61 instead of being fast on the horizontal table 1 might be mounted 70 on a horizontal bar toward which the table 1 may be moved.

The cranks 7¹ and 28 serving to turn the shafts 7, 24 and 25 by hand might be replaced by an interchangeable crank. 75

The position of the blowing nozzles with regard to those of the sucking device may be different from that shown in the drawing.

The joint of the sucking device may be 80 placed so as to be brought near to its lower end. Also the dimensions and forms of the various members of the machine may be different from those shown in the annexed drawing. 85

I claim as my invention:

1. A paper sheet feeding apparatus comprising a drive shaft, auxiliary shafts adjustable to and from each other and actuated by the drive shaft, pneumatic devices actuated by the auxiliary shafts for successively raising sheets of paper from a superimposed pile, and conveyors actuated by the auxiliary shafts for carrying sheets of paper as successively raised by the said pneumatic 95 devices.

2. A paper sheet feeding apparatus comprising a drive shaft, auxiliary shafts, a frame in which the said auxiliary shafts are journaled so as to be adjustable to and from 100 each other and to be driven from the drive shaft, pneumatic devices, means for actuating the pneumatic devices from the auxiliary shafts to successively lift the sheets of paper from a superimposed pile, and conveyors 105 also actuated by the auxiliary shafts for carrying the sheets of paper as successively raised by the said pneumatic devices.

3. A paper sheet feeding apparatus comprising a drive shaft, auxiliary shafts driven 110 from the drive shaft and adjustable to and from each other, pneumatic devices, means by which the pneumatic devices are operated from the said auxiliary shafts to successively raise sheets of paper from a superimposed pile, conveyors also actuated by the said auxiliary shafts, and gripper members connected to the conveyors for seizing sheets of paper as the same are successively raised by the pneumatic devices whereby the sheets 115 of paper are carried by the said conveyors.

4. A paper sheet feeding apparatus comprising a drive shaft, auxiliary shafts, frames in which the auxiliary shafts are journaled so as to be adjustable to and from 125 each other and to be driven from the drive shaft, an auxiliary frame pivotally connected to each frame in which the auxiliary shafts are journaled, a cylinder on said auxiliary frame, a piston in the cylinder, de- 130

- 5 vices for swinging the said auxiliary frame and operating the piston, a pneumatic device connected to the cylinder, the said devices for swinging the auxiliary frame and 5 actuating the piston being driven from an auxiliary shaft, and conveyers for carrying the sheets of paper as they are successively raised from a superimposed pile by the said pneumatic device.
- 10 5. A paper sheet feeding apparatus comprising a drive shaft, auxiliary shafts, frames in which the said auxiliary shafts are journaled so as to be adjustable toward and away from each other and to be driven 15 by the drive shaft, an auxiliary frame pivotally connected to each of the frames in which the auxiliary shafts are journaled, a cylinder connected to each auxiliary frame, a piston in each cylinder, a cam on each 20 auxiliary shaft, an arm associated with each auxiliary frame and actuated by the cam and corresponding auxiliary shaft to swing the said auxiliary frame and cylinder, a gear also on each auxiliary shaft, a gear 25 meshing with the aforesaid gear, a connecting rod extending between the piston in each cylinder and the second aforesaid gear, a pneumatic device associated with each cylinder, and conveyers by which the paper 30 sheets are carried as the same are successively raised from a superimposed pile by the said pneumatic device.
6. A paper sheet feeding apparatus comprising a drive shaft, auxiliary shafts, 35 frames in which the auxiliary shafts are journaled so as to be adjustable to position toward and away from each other and to be driven from the drive shaft, pneumatic devices operated by the auxiliary shafts for 40 successively raising sheets of paper from a superimposed pile, conveyer frames connected to the said frames in which the auxiliary shafts are journaled, sprockets mounted in each conveyer frame, endless chains 45 passing over the said sprockets, and gripper members carried by the endless chains and adapted to seize the sheets of paper as the same are successively raised by the said pneumatic devices whereby the sheets of 50 paper are carried forward by the said endless chains.
7. A paper sheet feeding apparatus comprising a drive shaft, auxiliary shafts, frames in which the auxiliary shafts are
- journaled so as to be adjustable to position 55 toward and away from each other and to be driven from the drive shaft, pneumatic devices operated by the auxiliary shafts for successively raising sheets of paper from a superimposed pile, conveyer frames connected to the said frames in which the auxiliary shafts are journaled, sprockets mounted in each conveyer frame, endless chains passing over the said sprockets, gripper members carried by the endless chains and 60 adapted to seize the sheets of paper as the same are successively raised by the said pneumatic devices whereby the sheets of paper are carried forward by the said endless chains, a table fixed below the said endless 65 chains, and guide members connected to the table for directing the path of the paper as the same is moved forward by the said grippers and endless chains.
8. A paper sheet feeding apparatus comprising a drive shaft, auxiliary shafts, frames in which the auxiliary shafts are journaled so as to be adjustable to position 70 toward and away from each other and to be driven from the drive shaft, pneumatic devices operated by the auxiliary shafts for successively raising sheets of paper from a superimposed pile, conveyer frames connected to the said frames in which the auxiliary shafts are journaled, sprockets mounted in each conveyer frame, endless chains 75 passing over the said sprockets, gripper members carried by the endless chains and adapted to seize the sheets of paper as the same are successively raised by the said 80 pneumatic devices whereby the sheets of paper are carried forward by the said endless chains, a table fixed below the said endless chains, a fixed guide member associated with one of the endless chains and attached to the 85 said table, and a movable guide member also attached to the said table and actuated by the other endless chain, the said guide members being adapted to direct the path of the paper as the same is moved forward by the 90 said grippers and endless chains.
- In testimony whereof I affix my signature in presence of two witnesses.

LEON MARTIN.
